Atty.

UNITED STATES PATENT OFFICE

CARL LOVGREN, OF EVANSTON, ILLINOIS

FOUNTAIN PEN

Application filed December 15, 1930. Serial No. 502,269.

This invention relates to a fountain pen of the kind in which a cartridge of ink is contained within a barrel, and it is concerned more particularly with certain improvements by which the cartridge is opened concurrently with repositioning of the pen stock upon the barrel end.

In the use of a fountain pen of the kind in question, a residue of wasted ink will always remain in each cartridge. In handling the cartridge, particularly when its seal is broken at the time the cartridge is placed in use, one's hands are apt to become soiled—an experience that is disagreeable at best. Except for difficulties, such as these, the cartridge type of pen is advantageous, inasmuch as extra supplies of ink can conveniently be kept on hand, or carried around to be available for immediate use, when required.

It is with the object in view of improving fountain pens of this character, and in particular of facilitating the opening of an ink cartridge, and of effecting a better drainage of ink therefrom, that this invention is concerned. A suggestive embodiment thereof is set forth in the accompanying drawings wherein—

Figure 1 is a longitudinal section through the pen in its entirety;

Fig. 2 is a transverse section on line 2—2 of Fig. 1;

Figs. 3 and 4 are enlarged fragmentary sectional views showing the pen stock in two different positions;

Fig. 5 which is a view in perspective looking toward the cartridge end shows in section the blade which opens the cartridge end adjacent the pen stock;

Fig. 6 which is a similar view shows the cartridge end opened in a manner somewhat differently; and

Fig. 7 which is a view similar to Fig. 2 shows a modified construction.

The pen assembly includes the usual cylindrical barrel A closed at one end by a wall 10 and at the other end by a removable pen stock B, and a cap C adapted for frictional mounting on either the pen stock or opposite barrel end, in accordance with usual practice. The inner end of the pen stock is

in the form of a nipple 11 exteriorly threaded for connection with screw-threads that are internally provided on the barrel adjacent its end. A shoulder 12 on the pen stock abuts the barrel end when the one part is screwed to final position relative to the other.

The present pen stock furnishes a mounting for the pen point or nib 15 to which ink is fed through a passageway 16 extending through the pen stock to its inner end, the passageway terminating, by preference, off-center diametrically opposite the nib. Adjacent the opening to this passageway is a knife blade 17 carried by the pen stock and extending inwardly into the barrel for an appreciable distance. This blade is of peculiar formation, in that it is curved somewhat in a plane transversely of the barrel axis, and is tapered to a point at its inner end 18, which lies substantially at the axis of the pen. The cutting edge 19 of this blade extends from its pointed end a substantial distance toward the pen stock.

The walls of the barrel near its opposite or closed end are desirably extended inwardly somewhat in a non-round formation, as suggested in Figs. 2 and 7. The cross section through the barrel at this point may be such as to provide a polygon—a square, hexagonal, or other form—or a single rib 24, as indicated in Fig. 7 may be substituted therefor. Within the barrel I arrange a cartridge D in the form of a vial having its inner end formed with a cross section which is complementary to that of the non-round end of the barrel, the purpose being to secure the cartridge against rotation therein. If desired, a cushioning pad 20 may be interposed between the barrel and cartridge end, as shown. The opposite cartridge end which lies proximate to the pen stock is sealed as by a closure or disk 21 adapted to be cut into by the blade for release of the ink supply.

In use, the pen parts are assembled with the ink cartridge first placed within the barrel, its inner end being received within the corresponding end of the barrel where it is held against rotation. The pen stock is next applied to the open end of the barrel and relatively advanced therein through interen-

gagement of the screw threads forming the connection therefor. In this operation, the pointed end of the knife blade advances to engage with the closure at the outer end of the vial. The initial contact of the knife blade is substantially at the center of the closure, but with continued rotation of the pen stock, the blade is required to travel through a circular path, and being disposed angularly with respect to the axis of the pen, the continued inward travel of the pen stock will result in the blade cutting from the closure a helical ribbon, such as is suggested in the drawing. This helical ribbon may be drawn outwardly by action of the knife blade to lead the ink as it drains from the vial, or if the blade be otherwise formed than is shown in Figs. 1 and 4, the ribbon will be inwardly pressed as it is produced. In either case, the closure is ruptured to permit flow of ink from within the vial into the space adjacent the inner end of the pen stock.

It may be found desirable to interpose a coiled spring 22 between the pen stock and proximate end of the vial, as shown, to maintain the vial in a fixed position where it cannot shift around or become loose. It may also be desirable to provide adjacent the vial a gasket 23 against which the spring end exerts pressure, the purpose being to prevent escape of ink from within the space below the vial along the wall of the latter. The ink released from the vial into the space below the pen stock is fed therefrom to the nib in the usual way.

The present pen is advantageous from many standpoints, due largely to the fact that vials containing ink may be kept on hand for use whenever fresh supply is needed. Such a contrivance is especially advantageous for those who require, when traveling, the use of fountain pens, and a convenient source of extra ink supply at hand. In such case a supply of vials may be carried along, and as needed they may be used in the manner described. In the handling of the vials there is no problem of escaping ink due to rupture of the closures therefor being deferred until after the pen stock is started on its way to final position following its assembly with the pen barrel.

I claim:

1. A fountain pen comprising a barrel open at one end, a pen stock mounting a nib and having a threaded connection with the open end of the barrel to form a closure therefor, a vial receivable within the barrel having means by which to lock non-rotatably therewith, a discripible closure at the vial end proximate to the pen stock, and offcenter means carried by the pen stock projecting towards the vial adapted to sever the closure thereof along a helical path when the pen stock is rotatively advanced to position within the open end of the barrel, the vial being

adapted to contain ink which is released upon discription of the closure whereby a supply of ink is assured to the nib carried by the pen stock.

2. In a fountain pen, the combination of a barrel open at one end, a pen stock carrying a nib having means for threaded connection with the open end of the barrel to form a closure therefor, a vial receivable within the barrel having means for preventing rotation of itself relative thereto, a discripible closure at the vial end proximate to the pen stock, and a pointed blade having an offcenter mounting on the pen stock extending therefrom toward the center of the vial closure adapted upon rotative advance of the pen stock to cut from the closure a ribbon along which ink contained within the vial may flow to the pen stock for delivery to the nib at the opposite end thereof.

3. In a fountain pen, the combination of a barrel open at one end, a pen stock mounting a nib at one end and formed at its opposite end for threaded connection with the open end of the barrel to provide a closure therefor, a blade projected eccentrically from the pen stock and inclined toward the barrel center, and an ink vial having a discripible closure at one end adapted for non-rotatable reception within the barrel, the blade being adapted to sever the vial closure when the pen stock is rotatively advanced upon the barrel end whereby the ink within the vial is released into the space adjacent the pen stock for delivery to the nib at the opposite end thereof.

4. In a fountain pen, the combination of a barrel open at one end whereon are formed screw-threads, an ink vial receivable non-rotatably within the barrel having one end provided with a discripible closure, a pen stock carrying at one end a nib and at its opposite end being provided with screw-threads for adjustable connection with the open end of the barrel, there being a passageway longitudinally through the pen stock by which ink may be fed therethrough to the nib, and a pointed blade carried by the pen stock at the inner end thereof adapted to sever the vial closure, the blade being inclined from an offcenter base toward the center of the closure and adapted to cut therefrom a helical ribbon along which ink may flow in passing to the pen stock.

5. In a fountain pen, the combination of a barrel open at one end whereon are formed screw-threads, an ink vial receivable non-rotatably within the barrel having one end provided with a discripible closure, a pen stock carrying at one end a nib and at its opposite end being provided with screw-threads for adjustable connection with the open end of the barrel, there being a passageway longitudinally through the pen stock by which ink may be fed therethrough to the

nib, a pointed blade carried by the pen stock at the inner end thereof adapted to sever the vial closure, and a spring encircling the blade and interposed between the inner end of the pen stock and the outer end of the vial to prevent longitudinal movement of the vial when the pen stock is screwed to innermost position.

6. In a fountain pen, the combination of
10 a barrel open at one end, a pen stock mount-
ing a nib at one end and formed at its oppo-
site end for threaded connection with the
open end of the barrel to provide a closure
therefor, a blade projected eccentrically from
15 the pen stock and inclined toward the barrel
center, an ink vial having a discerptible clo-
sure at one end adapted for non-rotatable
reception within the barrel, the blade being
adapted to sever the vial closure when the
20 pen stock is rotatively advanced upon the
barrel end whereby the ink within the vial
is released into the space adjacent the pen
stock for delivery to the nib at the opposite
end thereof, and a spring-pressed gasket fit-
25 ed into the barrel adjacent the vial closure
and adapted to seal that portion of the bar-
rel containing the vial to prevent congeal-
ment of the ink in the space between the bar-
rel and the vial.

30 7. A fountain pen having a barrel in
which is accommodated an ink vial provided
with a discerptible closure, means to hold
the vial against rotation and means connect-
ed to rotate in the barrel adapted to sever the
35 vial closure through a helical path.

8. A fountain pen having a barrel in
which is accommodated an ink vial provided
with a discerptible closure, means to hold
the vial against rotation, a blade within the
40 barrel movable through a helical path to
sever the vial closure, and means exteriorly
of the barrel connected to operate the blade.
